UNITED STATES PATENT OFFICE.

ALONZO LUTHER BAKER AND RUSSELL LOONIE BAKER, OF ALTOONA,
ALABAMA.

CULTIVATOR.

No. 833,660.

Specification of Letters Patent.

Patented Oct. 16, 1906.

Application filed May 11, 1906. Serial No. 316,419.

To all whom it may concern:

Be it known that we, ALONZO LUTHER BAKER and RUSSELL LOONIE BAKER, citizens of the United States, residing at Altoona, in the county of Etowah and State of Alabama, have invented a new and useful Cultivator, of which the following is a specification.

Our invention relates to cultivators; and it has for one of its objects the provision of a simple device of this character which may be easily adjusted and in which the breakage of the cultivator-teeth is reduced to a minimum.

A further object of our invention is the provision of an improved fender or plant-protector which may be readily adjusted to allow as little or as much earth as desired to be thrown about the plants being cultivated.

With these and other objects in view, as will hereinafter appear, our invention consists of the parts, improvements, and combinations of parts hereinafter set forth and pointed out in the claims, it being understood, however, that various changes in the form, proportion, and assemblage of parts may be resorted to within the scope of the claims without departing from the principle of our invention or sacrificing any of its advantages.

In this specification and in the drawings, forming a part thereof, the same reference characters are used to designate the same parts throughout.

In the drawings, Figure 1 is a side elevational view of one form of cultivator embodying our invention. Fig. 2 is a bottom plan view of a slightly-modified construction. Fig. 2' is a sectional detail on line 2 2, Fig. 2. Fig. 3 is a rear elevation of the cultivator shown in Fig. 1. Fig. 4 is a central vertical section through a portion of the cultivator shown in Figs. 1 and 3. Fig. 5 is a cross-sectional view on the line 5 5, Fig. 4; and Fig. 6 is a cross-sectional view on the line 6 6, Fig. 4.

Reference-numeral 1 indicates the beam of the cultivator, to which are bolted or otherwise secured the handles 2. Beneath the beam 1, and preferably somewhat to the rear of its middle, is secured the brace-ring 3, the beam being recessed to allow receiving the brace-ring, and thereby its lower surface to be flush with the lower surface of the beam. A number of holes 4 are provided in the ring 3

to permit the adjustment of the bars 5, 6, 7, 8, 55 9, and 10, which carry the cultivator-teeth 11. We preferably cause the bars 5 and 6 to lie in the same horizontal plane by offsetting one end of one of the bars and bolting their inner ends with a single bolt to the beam 1. 60 As shown in the drawings, this result is secured by making the bar 5 straight and by offsetting the bar 6 at its inner end where it crosses the bar 5, as shown. The upper rear bars 7 and 8 are made to lie in the same 65 plane with one another and with bars 5 and 6 by a similar construction, the bar 7 being straight and the end of the bar 8 being offset, as shown.

Beneath bars 7 and 8 we provide additional strengthening-bars 9 and 10, the bar 9 being offset where it crosses bar 10. The bars 7 and 8 are fastened to the beam by a single bolt, the head of which is sunk into a recess in the bar 7. The cultivator-teeth 11 75 are bolted to the bars 5 and 6 by bolts 12, the bolts being placed with their tapped ends uppermost, so that should a nut work loose it will be readily noticed, and when any adjustment of the device is made the nuts will be 80 readily accessible. Especial attention is directed to the fact that our cultivator is so constructed that every bolt in the framework may thus be placed with its tapped end uppermost, a construction which reduces the 85 danger of breakage because of the nuts working loose and which makes our device readily accessible by adjustment. The cultivator-teeth 11 are not perforated for the passage of bolts through bars 7, 8, 9, and 10, since we 90 have found that such a construction makes the teeth very liable to break. To remedy this defect, we provide depressions 13 in the teeth 11, as by stamping them therein before tempering, and also provide corresponding 95 projections on the lower rear bars 9 and 10, which fit snugly into the depressions in the cultivator-teeth. This construction makes a strong joint and dispenses with any necessity of breaking the fiber either of the teeth 100 11 or of the bars 9 and 10 by making holes therein.

Bolts 14 are passed through the bars 7, 8, 9, and 10, respectively, to secure them together. Between the said bars there are only 105 the teeth 11 to hold the bars apart, so that it is possible to secure the teeth therebetween as tightly as is desired. On the inner bolts

14 on each side of the beam are bolted braces 15, the opposite ends of the braces being secured to the beam 1 on top thereof and by the same bolt which secures the bars 7 and 8 thereto. The bolts 14, securing the bars 9 and 10 to the braces 15, also pass through bolt-holes in the brace-ring 3, and thus secure the bars firmly in position. Nuts or washers 14' are placed between the bars 7 and 8 and the brace-ring 3, so that the bars 5, 6, 7, and 8 and the bolts and nuts thereto may pass readily below the brace-ring. Links 16 are bolted to the front and rear bars on each side, respectively, to hold the sets of bars in parallelism.

Immediately beneath the beam 1 when the device is used, for example, as a harrow, as shown in Fig. 2, we provide a tooth 11, which is secured to its place in the manner already described. When cultivating a row of plants, we substitute therefor a plant protector or fender 16'. To support the said fender, a short metal bar 17 is secured to the cultivator-frame in the same way as are the teeth 11. The bar 17 projects downwardly at its rear end and has pivoted on said downwardly-projecting end the top bar 18 of the fender. To the said top bar 18 are secured the guard-blades 19 by means of short cross-bars 20. These guard-blades are designed to pass on each side of a row of plants and to protect the plants from falling dirt. To adjust the fender 16', we provide a slotted yoke 21, which is adjustably secured to the cross-bar of the handles 2 by a thumb-screw 22. A link 23 is secured at one end to the fender, and its opposite end passes through an opening in the yoke 21 and is headed upon the ex-

treme end. By this means we are able to set the fender so that it cannot fall below a predetermined position and yet can rise readily to pass over obstacles. The blades 19 are beveled or rounded off at their lower forward ends, so that they may readily pass over or through the ground.

We have placed the bolts which pivotally secure the rear cross-bars 7, 8, 9, and 10 to the beam 1 at substantially the center of the brace-ring 3, and the forward cross-bars 5 and 6 are pivoted to the beam at a point in advance of the point at which the rear bars are secured thereto. By this construction we are enabled to firmly support the cross-bars in any position, and particularly so in the ordinary or "A" position of the cultivator, as shown in Fig. 2 of the drawings.

From the foregoing description the operation of our improved cultivator will be apparent without further detailed statement.

Having thus described the invention, what is claimed is —

A guard attachment for harrows comprising a connecting-bar, a top bar pivoted thereto, cross-bars extending from the top bar, parallel blades secured to and extending from the cross-bars, and means extending from the top bar for adjustably engaging the handle of a harrow.

In testimony that we claim the foregoing as our own we have hereto affixed our signatures in the presence of two witnesses.

ALONZO LUTHER BAKER.
RUSSELL LOONIE BAKER.
